AIR CONDITIONING APPARATUS

Leroy Gale Huggins, Wilkinsburg, Pa., assignor
to Westinghouse Electric & Manufacturing
Company, East Pittsburgh, Pa., a corporation
of Pennsylvania

Application April 26, 1935, Serial No. 18,295

7 Claims. (CL 62—129)

My invention relates to air conditioning apparatus, more particularly to apparatus comprising a plurality of evaporators for cooling a stream of air, and it has for an object to provide improved apparatus.

A further object is, in connection with an air conditioning system comprising a plurality of compressors or compressor-condenser units and a plurality of evaporators connected to each compressor, to equalize the loads on the compressors and to cool the entire air stream at partial load.

A further object is to utilize standard developed apparatus.

In accordance with my invention, I arrange the evaporators in a plurality of groups, the air to be cooled passing through the groups in parallel and through the evaporators of each group in series, and I connect each compressor to the first evaporator in series in one group and to the second or subsequent evaporator in another group. Thus, the higher load of the first evaporators, due to the higher temperature of the incoming air, is distributed among a plurality of condensing units.

These and other objects are effected by my invention as will be apparent from the following description and claims taken in connection with the accompanying drawing, forming a part of this application, in which:

Fig. 1 is a diagrammatic view of apparatus embodying my invention; and

Fig. 2 is a diagrammatic view of a second embodiment of my invention.

Referring to the drawing in detail, I show an air conditioning chamber 10, which is connected to the enclosure to be air conditioned through a fan 11 and a duct 12. The fan 11 effects circulation of the air to be cooled through the chamber 10, the flow being from left to right in the embodiment illustrated in Fig. 1. The fan may be located at any suitable point in the air stream, and location at the outlet of the chamber 10 being but one example of a suitable location. Air to be treated is conveyed to the chamber through a duct 13 and may be either air withdrawn from the enclosure, outdoor air, or preferably a mixture of both, as is well known in the art.

The chamber 10 contains a plurality of refrigerating evaporators for cooling the air and may, of course, contain any other desired air treating elements. In the present embodiment, I show four evaporators, 14 to 17, the evaporators being arranged so that the air stream first passes

over the evaporators 14 and 15 in parallel for the first stage of air cooling, and the respective parallel portions then pass over the evaporators 16 and 17, respectively, for the second stage of air cooling. In other words, the group of evaporators 14 and 16 is in parallel with the group of evaporators 15 and 17 and the evaporators of each group are in series with each other with respect to air flow. The evaporators are preferably of the same capacity, for example, each evaporator may be a standard developed evaporator of 6-ton or 72,000 B. t. u. per hour capacity, or any other desired size. They may be of the usual cross-finned coil type, or of any other suitable type known in the art.

In the present embodiment, I provide two compressor-condenser units 18 and 19 for withdrawing vaporized refrigerant from the evaporators and for supplying liquid refrigerant thereto. Each unit includes a compressor 20, a motor 21 for driving the same, a condenser 22 and a liquid receiver 23. Each unit may be of standard design, having a capacity, for example, of 12 tons or 144,000 B. t. u. per hour, serving two of the above-mentioned evaporators. While I have shown separate compressor condenser units, the invention is not so limited but may be employed where only separate compressors are used.

Inasmuch as the air passing over the evaporators 14 and 15 is at higher temperature than the partially cooled air passing over the evaporators 16 and 17, the refrigerating load on the former will be greater than the load on the latter. As stated above, it is an object of the invention to impose equal loads on the compressors or the compressor condenser units, in order to provide the best performance with apparatus embodying standard developed elements, and also to cool the entire air stream at partial load. I accomplish this by connecting each compressor condenser unit to the first stage evaporator of one group and to a second stage evaporator of the other group.

Conduit means 24 connect the liquid receiver 23 of the unit 18 with the expansion valves 25 of the evaporators 15 and 16, and conduit means 25 connect the outlet ends of said evaporators with the suction of the compressor. Likewise, conduit means 26 connect the liquid receiver of the unit 19 with expansion valves 28 of the evaporators 14 and 17 and conduit means 27 connect the outlet ends of said evaporators with the suction of the compressor. The expansion valves are preferably of the type known as thermostatic

expansion valves, which control the admission of refrigerant in accordance with the superheat of the vaporized refrigerant discharged from the evaporator, thereby serving to supply such quantity of refrigerant as can be fully vaporized. Any other suitable form of pressure-reducing device or restrictor may be used.

Thermostatic control mechanism is preferably provided for controlling operation of the compressors. This mechanism includes a thermostat T that is responsive to the temperature of the air in the enclosure, and may be positioned either in the enclosure or in the stream of air returning from the enclosure to the chamber 10 through the duct 13. The thermostat T is provided with two switches 28 and 29 for controlling circuits 31 and 32, respectively, which supply current to the motors of the units 18 and 19, respectively. The thermostat and the switches are arranged so that the switch 29 is first closed upon increase in temperature to a predetermined value at which it is desired to maintain the enclosure, and so that the switch 28 is closed upon further increase to a slightly higher predetermined value. The switches open in reverse order upon decrease to slightly lower respective predetermined temperatures. It is to be understood that only the novel features of control are illustrated, and that any other control feature may be employed.

Operation

The operation of the above-described apparatus is as follows: The fan 11 effects circulation of air through the evaporators 14 to 17 in the chamber 10 in the manner described above.

When the air cooling load of the enclosure is sufficiently high to require operation of both compressors, the temperature rises to a value causing the thermostat T to close both switches. Energization of both circuits and operation of both units is effected, the unit 18 supplying liquid refrigerant to the evaporators 15 and 16 and withdrawing vaporized refrigerant therefrom, and the unit 19 supplying liquid refrigerant to the evaporators 14 and 17 and withdrawing vaporized refrigerant therefrom. One half of the air is partially cooled by the evaporator 14 and then further cooled by the evaporator 16 and the other half of the air stream is cooled by the evaporators 14 and 17, successively. As each unit serves one evaporator in the first stage of air cooling and one evaporator in the second stage of air cooling, it will be apparent that the loads on the two units will be equal.

When the temperature decreases to the lower value indicating that operation of one compressor will supply sufficient refrigeration, the switch 28 is opened by the thermostat T to shut down the unit 18. The unit 19 continues to operate to serve the evaporators 14 and 17. In this case, both portions of the air stream are cooled, one by the evaporator 14 and the other by the evaporator 17. Both evaporators are subject to the temperature of the incoming air and are subject to equal loads. However, the temperature is now lower than when operation of both units is required, so that the total load on the two evaporators and the unit 18 will be approximately the same, or not much greater than when both units are operating.

Further decrease in temperature results in opening of the switch 29 and shutting down of the unit 19 to discontinue further cooling of the air. Upon subsequent increase in tempera-

ture, the thermostat first closes the switch 29 to effect operation of the unit 19, and upon further increase in temperature, it closes the switch 28 to effect operation of the unit 18.

In Fig. 2, I show an embodiment of my invention in which a greater number of evaporators are required to supply the cooling load. Three groups of evaporators are arranged for cooling the air in three parallel portions, each group including two evaporators in series with respect to air flow, as in Fig. 1. In this case, the conduit means 24a and 25a connect the unit 18 to a third evaporator 33 in the first stage of air cooling of a third parallel portion of the air stream, as well as to the evaporators 15 and 16. 15 Conduit means 28a and 21a connect the unit 19 to a third evaporator 34 disposed in the second stage of air cooling, as well as the evaporators 14 and 17. In this case, the loads on the compressor condenser units are only partially balanced; however, the difference in load is only one-third of that which would be obtained if all three first stage evaporators were connected to one unit and the second stage evaporators connected to the other unit. The difference in loads 25 is reduced to a sufficiently low value to be unobjectionable.

From the above description, it will be seen that I have provided an arrangement in which the evaporators are so arranged as to equalize 30 or substantially balance the loads on the compressors or compressor condenser units to which they are connected, and so that all portions of air stream are cooled when only one unit is operating. This arrangement greatly facilitates 35 the use of developed apparatus of standard capacity.

While I have shown my invention in two forms, it will be obvious to those skilled in the art that it is not so limited, but is susceptible of various 40 other changes and modifications, without departing from the spirit thereof, and I desire, therefore, that only such limitations shall be placed thereupon as are imposed by the prior art or as are specifically set forth in the appended claims.

What I claim is:

1. In air cooling apparatus, the combination of a plurality of compressors, a plurality of evaporator elements connected to each compressor, and means for conveying air over said evaporator elements, said evaporator elements being arranged and distributed in parallel portions of the air stream so as to impose substantially equal loads on the compressors and so that each compressor is connected to evaporator elements in a plurality of parallel portions of the air stream.

2. In air cooling apparatus, the combination of a plurality of groups of evaporators, means for conveying air over said groups in parallel, the evaporators in each group being arranged to cool the air in successive stages, a plurality of compressors, each compressor being connected to at least one evaporator in each stage of air cooling and in each parallel portion of the air stream.

3. In air cooling apparatus, the combination of a plurality of compressors including first and second compressors, a plurality of evaporators connected to each compressor, means for circulating air over said evaporators, said evaporators and the circulating means being arranged so that one portion of the air stream is first cooled by an evaporator of the first compressor and then by an evaporator of the second compressor and another parallel portion of the air stream is first

cooled by an evaporator of said second compressor and then by an evaporator of a compressor other than the second compressor.

4. In air cooling apparatus, the combination 5 of a plurality of evaporators, means for conveying air over said evaporators, said evaporators being arranged in a plurality of groups that are in parallel with respect to air flow, each group comprising a first and a second evaporator over which the air flows in the order named, and a plurality 10 of compressors each connected to the first evaporator of at least one group and to the second evaporator of at least one other group.

5. In air cooling apparatus, the combination 15 of a plurality of compressors, a first and a second evaporator connected to each compressor, means for circulating air over said evaporators, said evaporators and the circulating means being arranged so that air flows over a first evaporator and then over a second evaporator and so that 20 each first evaporator is in series with the second evaporator of another compressor and in parallel with the first evaporator of another compressor with respect to air flow.

6. In air cooling apparatus, the combination of a plurality of compressors, a plurality of evaporators connected to each compressor, means for circulating air over said evaporators, said evaporators and the circulating means being arranged 5 so that each parallel portion of the air stream is cooled in successive stages by evaporators of a plurality of compressors and so that at least two evaporators of each compressor are in different air cooling stages. 10

7. In air cooling apparatus, the combination 15 of a plurality of evaporators arranged in groups, means for circulating air over the evaporators, the several groups being arranged in parallel and the evaporators in each group being arranged in series with respect to air flow, a plurality of compressors for said evaporators, each compressor being connected to a plurality of evaporators disposed in different groups and in different positions in the order of air flow. 20
